UNITED STATES PATENT OFFICE.

FRIEDRICH ADOLF LANGEN, OF COLOGNE-RIEHL, GERMANY.

DEVICE FOR MOISTENING COLOR-RIBBONS.

No. 849,148.

Specification of Letters Patent.

Patented April 2, 1907.

Application filed February 12, 1906. Serial No. 300,562.

To all whom it may concern:

Be it known that I, FRIEDRICH ADOLF LANGEN, a subject of the King of Prussia, residing at Stammheimerstrasse 25, Cologne-Riehl, Germany, have invented certain new and useful Improvements in Devices for Moistening Color-Ribbons, of which the following is a specification, reference being had therein to the accompanying drawings.

10 The color and fluid moistening or damping devices known at present consist either of rollers which are made of a material which absorbs moisture or which are covered with such material. The paint or fluid is supplied to the roller either by spreading it on the exterior thereof or by introducing it into an opening made in the roller for that purpose, the fluid then passing through holes from the interior to the surface of the roller. In the 15 first case the paint or fluid must be spread over the roller at short intervals. In the second instance it can be renewed at longer intervals, since the interior of the roller is able to contain a larger quantity of fluid.

20 As, however, it is essential with all devices for coloring that the color-ribbon, whether used as an absorbent ribbon or as a ribbon with the coloring-matter spread over it, should have on it always a regular limited 25 quantity of coloring-matter in order to obtain a uniform clear print, it is necessary that a regulation of the supply of coloring-matter should take place in two ways. Care is therefore taken that, first, in a state of rest 30 the damping-roller, and consequently the color-ribbon where it contacts with such roller, shall not be moistened too much, and, second, that it shall be possible to regulate the permeability of the damping-roller.

35 40 Only when these two conditions are fulfilled is it possible for the color-ribbon to have an even regulated amount of coloring-matter.

Figure 1 is a view in side elevation of my improved inking device. Fig. 2 is a similar view having the inking-roller removed. Fig. 45 3 is a view in side elevation of the roller of my device. Fig. 4 is a top plan view thereof. Fig. 5 is a view in side elevation of the means which I employ for securing the sections of my improved roller together. Fig. 50 6 is a top plan view of said means. Fig. 7 is a front elevation of a modification of my improved inking device, and Fig. 8 is an end view of the same.

In the annexed drawings are represented 55 two examples of such apparatus. According to Fig. 1 it consists of a tube *a*, which contains the fluid or coloring-matter, and of the roller *b* as moistener or damper. The tube *a* is closed at the top by a screw cap or valve 6c *c* and at the bottom by a plug *d*. In the lower end above this plug are many small apertures *e*, arranged in line longitudinally of the axis of the tube *a*, the function of said apertures being to permit the paint contained in *a* to pass through them.

The damping-roller *b* is composed of felt or cloth in the form of a hollow cylinder, which may, if desired, be built up from separate disks, as shown. The two ends of the cylinder are closed by metal disks *f*, which can be drawn together by screws in order to regulate by compression the absorbing capacity of the roller.

The apparatus is so arranged that the small 75 apertures *e* in the fluid-receptacle *a*, on which latter the damping-roller *b* is mounted, shall be opposite the color-ribbon *g*, led over the said roller *b*, and as a result the apertures *e* are closed by the roller, when the apparatus 80 is at rest, with the coöperation and under the influence of the pressure resulting from the tension of the color-ribbon.

In Figs. 7 and 8 I have shown another form 85 of my improved inking device, in which I employ a frame *f'* for supporting the several parts thereof. In the modification I bend a portion of the tube at right angles to the remainder of the tube, and this portion extends through openings formed in one extremity of the said frame and lies in a horizontal plane. This horizontal portion is provided with a plurality of small apertures *e*, which feed the coloring liquid to an absorbent roller *b*, which is mounted on said horizontal 90 portion. Mounted in said frame above said inking-roller is a ribbon-holding roller *g'*, around which is wrapped the ribbon *g* of said tube *a*. The vertical portion forms the receptacle for the coloring-matter and has its 95 uppermost extremity closed by means of a cap *c*.

Having now particularly described and ascertained the nature of the said invention and in what manner the same is to be performed, I declare that what I claim is—

A device of the character described comprising a frame, a ribbon-roller mounted in

one extremity of said frame, an impervious roller mounted at the other extremity of said frame, a substantially L-shaped tube having its one end perforated and mounted in said frame and forming a bearing for said impervious roller, the stem of said L-shaped tube forming an ink-receptacle, said impervious roller adapted to receive the ink through the

perforations of the foot of said L-shaped tube, substantially as described.

In testimony whereof I have affixed my signature in the presence of two witnesses.

FRIEDRICH ADOLF LANGEN.
